(57) **CLAIM**

The ornamental design for a rugged portable computer, as shown and described.

DESCRIPTION

FIG. 1 is a top, left perspective view of a rugged portable computer in a closed configuration, with the handle in a carry position;

FIG. 2 is a top, right perspective view of the rugged portable computer in a closed configuration, with the handle rotated downwards in a stored position;

FIG. 3 is a front perspective view of the rugged portable computer in an open configuration, with the handle in a carrying position;

FIG. 4 is a right perspective view of the rugged portable computer in an open configuration, with the handle rotated downwards in a stored position;

FIG. 5 is a top view of the rugged portable computer when closed;

FIG. 6 is a bottom view of the rugged portable computer when closed;

FIG. 7 is a front view of the rugged portable computer when closed;

FIG. 8 is a front view of the rugged portable computer when open;

FIG. 9 is a rear view of the rugged portable computer when closed;

FIG. 10 is a right view of the rugged portable computer when closed;

FIG. 11 is a right view of the rugged portable computer when open;

FIG. 12 is a left view of the rugged portable computer when closed; and,

FIG. 13 is a left view of the rugged portable computer when open.
